Haworth.com, Atwell chair, Dec. 20, 2017, <http://www.haworth.com/products/seating/lounge-chairs/atwell>.*Primary Examiner — David Muller*Assistant Examiner* — Nathan Johnston(74) *Attorney, Agent, or Firm* — Warner Norcross & Judd LLP(57) **CLAIM**

The ornamental design for an arm for a chair, as shown and described.

DESCRIPTION

FIG. 1 is a front perspective view of the arm for a chair embodying the new design;

FIG. 2 is a left side view thereof;

FIG. 3 is a front view thereof;

FIG. 4 is a rear view thereof;

FIG. 5 is a top view thereof; and,

FIG. 6 is a bottom view thereof.

FIGS. 1-6 show an arm for a chair in broken lines. The portions shown in broken lines are for environmental purposes only and form no part of the claimed design.

1 Claim, 6 Drawing Sheets
